UNITED STATES PATENT OFFICE.

THOMAS MORRISON, OF BRADDOCK, PENNSYLVANIA.

CHIMNEY-VALVE FOR HOT-BLAST STOVES.

SPECIFICATION forming part of Letters Patent No. 691,476, dated January 21, 1902.

Application filed January 15, 1901. Serial No. 43,358. (No model.)

To all whom it may concern:

Be it known that I, THOMAS MORRISON, of Braddock, in the county of Allegheny and State of Pennsylvania, have invented a new 5 and useful Chimney-Valve for Hot-Blast Stoves, of which the following is a full, clear, and exact description, reference being had to the accompanying drawings, forming part of this specification, in which—

10 Figure 1 is a horizontal section of a hot-blast stove, showing one of my improved valves in horizontal section and another in plan, both valves being open. Fig. 2 is a vertical central section, on a larger scale, showing 15 one of the valves in closed position.

Heretofore the chimney-valves of hot-blast stoves have generally been constructed either as sliding gate-valves or as water-cooled mushroom-valves operated by stems which extend 20 vertically to the outside of the valve-casing; but by reason of the dust which comes out from the stove and the grease and moisture which are carried in by the cold blast the seats of such valves are apt to become clogged 25 and to cause the valves to fit unevenly, thereby occasioning leaks, which when the cold blast enters the stove permits a portion of it to escape wastefully into the stack. Such valves are also difficult of access. The leak 30 is hard to detect and hard to stop. It is the purpose of my invention to correct these evils and also to cause the stove to act more uniformly by employing two or more chimney-valves and outlets at different parts of the 35 periphery of the stove.

My invention consists in employing at the stack-outlet of the stove a disconnected chimney-valve comprising a hollow or tubular section which when it is in its open position fits 40 the outlet-port of the stove and communicates with the chimney-flue and which is provided with a plate so constructed that when it is drawn back to open the outlet-port of the stove it will move over and close the port of 45 the flue. When the valve is thus disconnected from the stove, the outlet-port is tightly closed by a suitable door.

In the drawings, 2 represents the shell of the hot-blast stove, having an outlet-port 3 50 for the exit of the hot gases on their way to the chimney.

4 is the chimney-flue, at the end of which is an elevated box or casting 5, on whose surface is a port 4'.

6 is the hollow valve, which is slidably 55 mounted on the casting 5 and has a port 7, which when the valve is open registers with the port 4', and has a plate 8, which when the valve is moved back to closed position covers and closes the port 4'. The valve may be 60 moved by suitable lever mechanism 9, and in its open position when the ports 7 and 4' are in register its end enters and fits the stove-port 3, so that the hot gases from the stove will pass directly through the valve and into 65 the chimney-flue. When the valve is to be closed, it is drawn back so as to shut the opening 4' and to expose the port 3, whereupon a door 10, suitably shaped to fit this port neatly, is applied to it and fastened so as to make 70 a tight joint. The door is exposed to view, and any leakage which may occur when it is closed can readily be perceived and corrected. The importance of this in the working of the stove will be appreciated by those who are 75 skilled in the art.

The invention enables me to dispense with the valve heretofore used in the chimney-flue, leaving in the stove only one valve which is apt to leak—namely, the hot-blast valve. 80 It also enables me to regulate the draft on the stove when desired by drawing back the valve somewhat, whereby the port 4' may be partly closed and an opening for air afforded at the end of the valve, both of which will 85 have the effect of lessening the draft.

The simplicity of construction of my valves enables me with economy to employ two or more of them, as shown at A B in Fig. 1, arranged at different parts of the circumference of the stove, so that the draft from the stove is distributed and is not localized at a single point, as is the case where only one valve and outlet-flue are employed.

I claim—

1. A hot-blast stove having an outlet-port, a chimney-flue, an elevated box 5 connected with the chimney-flue, and a hollow chimney-valve adapted to fit the outlet-port of the stove and mounted on the said box, said valve 100 being movable on the box to and from the outlet-port, and having a portion which in its

motion covers and uncovers respectively the opening of said box; substantially as described.

2. A hot-blast stove having a plurality of 5 outlet-openings, chimney-flues adjacent thereto, and hollow chimney-valves adapted to fit said outlet-ports and to be moved toward and from the same, and having portions which in such motion cover and uncover respectively 10 the ports of the chimney-flues, said outlet-

ports being situate at different parts of the periphery of the stove and being adapted thereby to distribute and equalize the draft on the stove; substantially as described.

In testimony whereof I have hereunto set 15 my hand.

THOMAS MORRISON.
